CLAIM

The ornamental design for a shoe, as shown and described.

DESCRIPTION

FIG. 1 is a bottom perspective view of a shoe showing my new design; and,

FIG. 2 is a bottom view thereof.

The broken line immediately adjacent to and surrounding the shaded area defines the peripheral bounds of the claimed design and forms no part thereof. The broken lines depicting the remainder of the shoe form no part of the claimed design.

1 Claim, 2 Drawing Sheets(56)
